CLAIM

The ornamental design for a comestible container, as shown and described.

DESCRIPTION

FIG. 1 is a perspective view of a comestible container, showing our new design;

FIG. 2 is a top view of the embodiment shown in FIG. 1; FIG. 3 is a bottom view of the embodiment shown in FIG. 1;

FIG. 4 is a side view of the embodiment shown in FIG. 1; FIG. 5 is another side view of the embodiment shown in FIG. 1;

FIG. 6 is a front view of the embodiment shown in FIG. 1; FIG. 7 is a rear view of the embodiment shown in FIG. 1; FIG. 8 is a perspective view of the embodiment shown in FIG. 1 in a first open configuration;

FIG. 9 is a bottom view of the embodiment shown in FIG. 1 in a second open configuration;

FIG. 10 is another perspective view of the embodiment shown in FIG. 1 in the first open configuration; and, FIG. 11 is another perspective view of the embodiment shown in FIG. 1 in the second open configuration.

The broken line disclosure forms no part of the claimed design.
